UNITED STATES PATENT OFFICE.

JOHN W. BURTON, OF EYE, AND GEORGE PYE, OF IPSWICH, ENGLAND.

IMPROVEMENT IN MODE OF TREATING FLAX, HEMP, AND OTHER FIBROUS MATERIAL.

Specification forming part of Letters Patent No. **18,801**, dated December 8, 1857.

To all whom it may concern.

Be it known that we, JOHN WATSON BURTON, of Eye, in the county of Suffolk, and GEORGE PYE, of Ipswich, in the same county, England, flax manufacturers, subjects of the Queen of Great Britain, have invented or discovered a new and useful Improvement in Treating Flax, Hemp, and other Fibrous Matters Requiring Like Treatment; and we, the said JOHN WATSON BURTON and GEORGE PYE, do hereby declare the nature of the said invention and in what manner the same is to be performed to be fully described and ascertained in and by the following statement thereof—that is to say:

Our invention consists of treating the fibrous parts of flax, hemp, or other fibrous matter requiring like treatment (after being separated from the boon or woody matter, or without having first separated the woody matter or boon) by subjecting the same to the action of water impregnated or combined with fuller's-earth and with steam, and then to boil the fibrous matters. During the process of boiling the fibers they are to be alternately closely pressed together and allowed to expand from time to time.

The above constitutes the nature of our invention. In addition to such process, and for the purpose of further improving the fibrous material, it may be subsequently treated as follows: The fluid having been drawn off, the fiber is to be allowed to stand for a time under pressure and afterward to be subjected to the action of a machine having pressing-rollers and crimping-rollers, the process finishing with pressing-rollers in order to remove the effect of crimping. The surfaces of the rollers are, during such process of pressing and crimping, wiped by felts or cloths. The fiber is next to be hacked and spun. This latter process of pressing and crimping by machinery may be beneficially applied to flax, hemp, and other fiber prepared by other processes, in which cases the fibers would be dampened by the first pressing-rollers. In other respects the treatment between crimping and pressing rollers is the same as above explained.

Having thus stated the nature of our said invention, we will proceed more fully to describe the manner of performing the same.

In the drawings, Figure 1 shows a side ele-

vation of machinery used for subjecting flax, hemp, and other fibrous matters to the action of fuller's-earth in water, and for boiling such fibrous matters in water combined with fuller's-earth. Fig. 2 is a vertical section of the apparatus or machinery. Fig. 3 shows a horizontal section, the upper parts or gearing being removed. Besides the above the drawings also exhibit the machine in ground plan and longitudinal section.

In each of these figures the same letters are used to indicate the same parts.

a *a* is a rectangular vessel, having a false perforated bottom at *b*, on which the flax, hemp, or other similar vegetable substance is to be placed, and between it and the follower *c*. This vessel is then filled up to the under side of the follower with water mixed with fuller's-earth, such mixing being first made in a separate vessel, and the impurities being allowed to subside before the water impregnated with the fuller's-earth is introduced into the vessel *a*. The quantity of fuller's-earth used may be varied; but we generally employ at the rate of about one pound to every five gallons of water.

d is a steam-pipe, by which free steam can be introduced into the lower part of the vessel *a*.

The flax, hemp, or other similar vegetable matter is to be subjected to the treatment before mentioned—or, in other words, to being boiled and alternately pressed and allowed to expand until the epidermis is sufficiently softened and the coloring-matter or albumen extracted. During this process there may be a constant flow of fuller's-earth water admitted into the vessel *a*, and a quantity run off therefrom, and when it is found that the water flowing off does not show the presence of coloring-matter the further supply and outgoing of the water are to be stopped and the fibers in the vessel *a* are to be boiled up in the liquid. The boiling is accomplished by admitting steam to flow more freely into the lower part of the vessel after stopping the flow of water into and from the vessel. During such boiling process the follower is caused to be raised and lowered by the gearing shown by the drawings, the nature of which will be readily understood by reference to the drawings, and therefore will not require further description.

When the matters in the vessel have been thoroughly boiled, the fluid is to be drawn off, the follower being pressed downward so as to compress the fibers until all the water has been expressed therefrom, and we retain the fibers subjected to pressure for some time—say four hours or more—after the water has been drawn off, the same being in order to mollify and partially dry the fibers. The steam used by us is from forty to sixty pounds on the square inch in the boiler; but this may be varied.

Having thus described the process constituting our invention, we would remark that the fibers are now in a state to be treated by the machinery, which we will now proceed to describe, or the fibers before being subjected to the action of such machinery may be dried and acted on in the dry state, and we would state that we find that by reason of our having used fuller's-earth water the fibers, though dry, will spin more freely than when they are dry after having been prepared by other processes.

Fig. 5 shows a plan, and Figs. 6 and 7 are side views, of a machine for pressing, crimping, and pressing fibers. *ff* are pressing-rollers, between which the moist flax, hemp, or other similar fibers, after they have undergone the process above described, are to be run. *gg* are three pairs of crimping-rollers. More or less of these may be used; but we prefer three pairs. *hh* are two or more pressing-rollers to take out the impressions of the crimping-rollers. The fibers are laid on an endless belt, *k*, and after being seized by the rollers *ff* pass from thence to and between the

others, whereby, before they leave the machine, they will have been pressed, crimped, and again pressed.

It is desirable that the two pairs of pressing-rollers should be subjected to considerable pressure, and therefore each pair is provided with weighted levers *rr*, such as are shown in Figs. 5 and 6; but other arrangements of parts may be used.

A felt or fabric may be used to constantly moisten the surface of the upper pressing-rollers. We would state that this process of pressing, crimping, and pressing by pairs of rollers is very important, for by such means the fibers are better prepared for hackling than by any other process we are acquainted with.

We do not claim merely heating or boiling fiber in water; but

What we claim as our invention is—

The above-described mode of treating flax or fibrous matters requiring like treatment, the same consisting in subjecting such, as described, to the action of a press and to water impregnated with fuller's earth and heated or boiled.

JOHN WATSON BURTON.
GEORGE PYE.
